Wilson M. Howard

UNITED STATES PATENT OFFICE.

CHARLES H. HOYT, OF BEVERLY, MASSACHUSETTS, ASSIGNOR TO UNITED SHOE MACHINERY CORPORATION, OF PATERSON, NEW JERSEY, A CORPORATION OF NEW JERSEY.

FASTENER-SUPPLYING MECHANISM.

Application filed June 13, 1922. Serial No. 568,019.

This invention relates to distributors such as are used in supplying fasteners to the driving instrumentalities in fastener-inserting machines, and is illustrated as embodied in a distributor of the type commonly used on pulling over machines, although the invention is not thus limited in its applicability.

An object of the invention is to provide, in a distributor, means for selectively closing different raceways or fastener guides, i. e., for preventing delivery of fasteners from said raceways, as for example in adjusting a machine for inserting more or fewer fasteners or for varying the locations of the fasteners in the work. To attain this object in the construction shown a set of novel separate closing members, one adjacent to each raceway, is provided so that any one or more of these members may be operated to close the corresponding raceways selectively as may be desired. In the illustrated form of the invention, spring-pressed plungers for actuating the closing members are mounted back of the usual removable end block or face plate, to be engaged and retracted thereby to hold the corresponding members in inoperative position, and each plunger is provided with means such as a removable portion for shortening its length so that it will not be held inoperative by the end block and will therefore be held forward under the influence of its spring to rock the corresponding closing member into the adjacent raceway to close it.

Another object of the invention is to improve distributors of this type by providing means for preventing the spilling of fasteners when the end block and separator plate are removed, as is sometimes necessary when the fasteners jam in the distributor. In the illustrated embodiment of the invention, all of the above described plungers that are not already in advanced position are moved forward by their springs when the end block is removed, so that at that time all of the raceways are closed to prevent spilling of fasteners.

The above and other features of the invention will be apparent from the following description of an illustrative embodiment

of my invention shown in the accompanying drawings, in which

Fig. 1 is an isometric view, partly broken away, showing the end of the raceway plate 55 of a distributor and parts associated therewith; and

Fig. 2 is a front elevation of part of the raceway plate shown in Fig. 1.

As shown in the drawings, my invention 60 may be embodied in a distributor of the type which is provided with a raceway plate 10 in which are formed a plurality of fastener-guiding raceways 12. Feeding means is provided, including a separator plate 14 65 which is formed with the usual inclined slots 16 and which is arranged to reciprocate across the ends of the raceways 12 to separate a single fastener from those in each of the several raceways. The fasteners so 70 separated are delivered to chutes 18 formed in a removable end block or face plate 20, locked in position by spring pressed plungers 22 controlled by finger pins 24. The end block 20 carries a plate 26 which extends up above the bottom parts of raceways 12 and the reciprocating separator plate 14. These parts may be, and are shown as being, the same as the corresponding parts 75 fully described in United States Letters Patent No. 1,002,422, granted Sept. 5, 1911, on application of R. F. McFeely.

Adjacent to each raceway 12, and parallel thereto, is a socket in which is mounted a plunger 30 pressed outwardly or forwardly 85 by a coil spring 32 and having pivotally mounted thereon a finger 34 which slides in an arcuate depression in the raceway plate 10, so that it has a combined lengthwise and rocking movement into and across the corresponding raceway 12 through an opening in the side thereof below the heads of the tacks when the plunger 30 is pressed outwardly by its spring 32. Thus when the end block 20 is removed all of the plungers 80 90 95 30 are pressed outwardly by their respective springs, so that all of the raceways are closed and spilling of tacks is avoided when the separator plate is afterwards removed.

Each plunger 30 is formed with a removable portion such as a tap screw 36, and when it is desired selectively to shut off any

- one or more of the raceways 12, the end block 20 is removed and tap screws 36 are removed from plungers 30 corresponding to the raceways 12 which are to be closed.
- 5 When the end block 20 is replaced the plungers 30 shortened by removal of their screws 36 will not be operated by engagement with block 20 and the corresponding raceways 12 will remain closed.
- 10 While one embodiment of my invention has been illustrated and described, it is not my intention to limit its scope thereby or otherwise than by the terms of the appended claims and it is also to be understood
- 15 that while the invention is illustrated by reference to a distributor adapted for use with tacks or nails, in many of its aspects it is not dependent upon the form of the fasteners.

Having described the invention, what I claim as new and desire to secure by Letters Patent of the United States is:—

1. A distributor comprising, in combination, a plurality of fastener-guiding raceways corresponding in number to the number of fasteners that can be delivered from the distributor at a time, fastener-separating means for separating fasteners from the lower ends of said raceways, and a plurality of raceway-closing devices, one for each of said raceways, comprising pivoted members movable to change the locations of their axes while entering the raceways laterally to close them, said members being manually controllable thus to close and to maintain continuously closed, at the will of the operator, any selected number of the raceways.

2. A distributor comprising, in combination, a plurality of fastener-guiding raceways corresponding in number to the number of fasteners that can be delivered from the distributor at a time, fastener-separating means for separating fasteners from the lower ends of said raceways, and a plurality of raceway-closing devices, one for each of said raceways, comprising curved fingers slidably movable lengthwise in predetermined paths transversely of the respective raceways below the heads of the fasteners and manually controllable each independently of the others to close and to maintain continuously closed, at the will of the operator, any selected number of the raceways.

3. A distributor comprising, in combination, a plurality of raceways, separating means for separating fasteners from the lower ends of said raceways, and a plurality of pivotally mounted fingers, one adjacent to each raceway, each controllable independently of the others and movable both bodily and about its axis to project a portion thereof through an opening at the side of the raceway to close the raceway and maintain it continuously closed at the will of the operator.

4. A distributor comprising, in combina-

tion, a plurality of raceways, means for separating fasteners from said raceways, a corresponding plurality of fingers each mounted for combined rocking and lengthwise movement into the corresponding raceway to close it, and spring means for thus moving each of said fingers independently of the others.

5. A distributor comprising, in combination, a plurality of raceways, means for separating fasteners from said raceways, a corresponding plurality of raceway-closing fingers adjacent to the different respective raceways, a plurality of springs, one for each finger, for operating said fingers to close the adjacent raceways, and a device common to all the fingers for withdrawing the fingers to idle positions against the resistance of their springs.

6. A distributor comprising, in combination, a raceway plate having a plurality of raceways formed therein and a socket beside and substantially parallel to each raceway, a spring-pressed plunger in each of said sockets, and a raceway-closing finger mounted on each of said plungers to be operated thereby to close the corresponding raceway.

7. A distributor comprising, in combination, a plurality of raceways, feeding means associated therewith, a displaceable member at the lower ends of the raceways, and means to close all of said raceways above the feeding means when said member is displaced.

8. A distributor comprising, in combination, a plurality of raceways, separator means therefor, a displaceable member at the lower ends of the raceways, and means rendered operative by displacement of said member to close the raceways above the separator means.

9. A distributor comprising, in combination, a plurality of raceways, a separator device therefor, a corresponding plurality of raceway closing devices respectively adjacent to the several raceways and located above the separator device, a member removable to afford access to the lower ends of the raceways, and means for operating said closing devices simultaneously to close the raceways when said member is removed.

10. A distributor comprising, in combination, a plurality of raceways, a separator device therefor, a removable member at the lower ends of the raceways, and a corresponding plurality of spring pressed plungers engaging said member and each carrying a raceway closing finger above the separator device, so constructed and arranged that on removal of said member the plungers move the fingers across their respective raceways to close them.

11. A distributor comprising, in combination, a raceway for fasteners, a device movable into or out of position to obstruct the movement of fasteners along the raceway,

5 said device comprising a controlling member movable lengthwise of the raceway and a finger movable into the path of the fasteners in response to movement of said member, and
means adjacent to said device for successively feeding fasteners from the raceway when they are not blocked by said finger.

10 12. A distributor comprising, in combination, a raceway for fasteners, a device movable into or out of position to obstruct the movement of fasteners along the raceway, said device comprising a controlling member movable lengthwise of the raceway and a finger pivoted on said member and arranged
15 to engage a portion of the distributor to be turned thereby into or out of the path of the fasteners in response to movement of said member, and fastener-feeding means adjacent to said device.

20 13. A distributor comprising, in combination, a raceway for fasteners, a member removable to afford access to the lower end of said raceway, and a controlling device movable into or out of position to obstruct the movement of fasteners along the raceway and arranged to be held in inoperative position by said removable member and to be released to render it operative upon the removal of said member, said controlling device including means whereby it may be rendered operative to obstruct the movement of the fasteners also when said member is in place.

25 14. A distributor comprising, in combination, a raceway for fasteners, a member removable to afford access to the lower end of said raceway, and a device arranged to be controlled by said removable member to render it operative to obstruct movement of fasteners along the raceway when said member is removed and to render it inoperative when said member is in place, said device including means whereby it may be rendered continuously operative to obstruct the movement of the fasteners independently of the control of said member.

30 15. A distributor comprising, in combination, a raceway, a removable member at the end of said raceway, a raceway-closing finger, and a spring pressed member for operating said finger having a removable portion engaging said end member to hold the raceway closing finger in inoperative position, and so constructed and arranged that when said portion is removed the raceway remains closed.

35 16. A distributor comprising, in combination, a raceway, a removable end block at the lower end of said raceway, and a spring-pressed raceway closing device having a removable portion to engage said block to hold the closing device in inoperative position.

40 17. A distributor comprising, in combination, a plurality of raceways, a pivotally mounted raceway closing finger adjacent to

each raceway and mounted to oscillate across the raceway to close it, and a finger-operating plunger parallel to each raceway.

45 18. A distributor device comprising, in combination, a source of supply of fasteners, a plurality of feed guides each directing a series of fasteners from said source, said guides having a common removable portion, means for selectively closing one or more guides, and means rendered operative by removal of said common portion for closing all of the guides not previously selectively closed.

50 19. A distributor comprising, in combination, a raceway for fasteners, a separator for controlling delivery of fasteners from said raceway, a member displaceable at the will of the operator to afford access to the interior of the distributor, and means for insuring closure of the raceway whenever said member is displaced.

55 20. A distributor comprising, in combination, a plurality of raceways, separating means for controlling delivery of fasteners from said raceways, a member displaceable at the will of the operator to afford access to the lower ends of the raceways, devices movable into or out of position to close the different respective raceways, and means for insuring closure of all the raceways by said devices whenever said member is displaced.

60 21. A distributor comprising, in combination, a raceway for fasteners, a separator for controlling delivery of fasteners from said raceway, a member displaceable at the will of the operator to afford access to the interior of the distributor, and a device controlled by said displaceable member for preventing movement of fasteners along the raceway when said member is displaced.

65 22. A distributor comprising, in combination, a plurality of raceways, devices for closing the different respective raceways, said devices being movable independently of one another to close some of the raceways while the other raceways remain open, a member displaceable at the will of the operator to afford access to the lower ends of the raceways, and means for insuring the closure of said other raceways whenever said member is displaced.

70 23. A distributor comprising, in combination, a raceway, a member displaceable at the will of the operator to afford access to the lower end of said raceway, and a raceway closing device arranged to be engaged by said displaceable member to hold said device in inoperative position, said device including a portion displaceable at will to prevent it from being held in inoperative position by said member.

75 24. A distributor comprising, in combination, a raceway, a member displaceable at the will of the operator to afford access to the lower end of said raceway, and a raceway

closing device comprising a member movable into or out of the raceway and a plunger movable lengthwise of the raceway to control said member, said plunger being arranged to be held by said displaceable member in position to maintain the raceway closing member inoperative and having means

for varying its effective length to permit the closing of the raceway by said closing member when the displaceable member is in operative position.

In testimony whereof I have signed my name to this specification.

CHARLES H. HOYT.
